DOME FOR CONCRETE STRUCTURES.

1,254,919.

Specification of Letters Patent. Patented Jan. 29, 1918.

Application filed January 12, 1917. Serial No. 141,986.

To all whom it may concern:

Be it known that we, EDWARD C. MARQUA, HANS VON UNWERTH, and JOHN H. BYRD, citizens of the United States, residing at 5 Kansas City, in the county of Jackson and State of Missouri, have invented certain new and useful Improvements in Domes for Concrete Structures; and we do declare the following to be a full, clear, and exact description of the invention, such as will enable others skilled in the art to which it appertains to make and use the same, reference being had to the accompanying drawings, and to the letters and figures of reference 10 marked thereon, which form a part of this specification.

Our invention relates to domes for concrete slab construction, and is an improvement on our co-pending application, Serial 20 No. 121,605, filed September 22, 1916, the principal object of the present invention being to provide for expansion of the dome, and thereby obviate necessity for special sizes for variously spaced beams and to 25 provide for interlocking the domes longitudinally to retain their alinement.

It is also an object of the present invention to provide a detail arrangement of the body portions of the domes, which will permit the same to fold and thereby facilitate 30 storing and shipping.

In accomplishing these objects we have provided details of structure, the preferred forms of which are illustrated in the accompanying drawings, wherein:

Figure I is a perspective view of a partially formed concrete floor slab, illustrating the arrangement of domes on the soffit boards and the supports of the soffits on their studs.

Fig. II is a transverse section through a part of a slab, illustrating the floor beams and the combination of the domes therewith.

Fig. III is an inverted perspective view of one of the domes, parts being broken away for better illustration.

Fig. IV is a detail perspective view of one of the body portions of a dome, in its collapsed position.

Fig. V is an inverted perspective view of a dome, illustrating a temporary batten.

Referring more in detail to the drawings: 55 1—1' designate the body portions of our improved dome, each of which comprises a

side board 2 and top member 3, the top member being here shown to comprise a single board, although we do not wish to be limited to this detail, as it is apparent that either the top or the sides of the body members may be made up in several separate pieces and that the pieces of each member may be rigidly and permanently connected by the battens 4—5. The battens 4 and 5 not only serve to stiffen the body members to which they are connected, and when the latter are made up in several pieces to connect the pieces, but they also serve to carry the hinges 6, whereby the members 2—3 are connected. The preferred arrangement is 60 that wherein the edge of the top member 3 overlies and is supported by the upper edge of the side member 2, and the arrangement being further such as that when the members are extended in functional position, the 65 parts 2—3 will extend at an obtuse angle to each other to taper the floor beam and brace the dome member against collapse. There may be any suitable number of paired battens 4—5 throughout the length of the dome 70 member, although one pair at each end is ordinarily sufficient.

In ordinary building construction, an arch between floor beams is rarely less than 20 inches across at the bottom and 18 inches 85 at the top and in order to conform to such conditions, we construct the dome to comply with this width. As each dome is made up of a pair of body members, the upper member 3 of each member is made 9 inches in 90 width so that, when combined with the other body member, the top of the dome will be 20 inches across and adapted for forming the minimum width of the arch, each member of the body being identical in construction with the other, although the pairs are arranged in rights and lefts, as the side and top parts of each member are not interchangeable owing to the incline of the floor beams and to the fact that the depth of 95 the arch does not ordinarily equal one-half of its width.

In order to rigidly connect paired members of the dome when the latter is in use, we provide the top of one of the body portions of a pair with a hook 8 which is adapted for taking into an eyelet or the like 9 on the top of the mating body member, and in order to space the members and retain the dome in functional condition, we pro- 100 105 110

vide interior diaphragms 10, which are adapted for abutting against opposite sides 2 and for seating in shoulders 11 on the side battens 4. The ends of the diaphragms are 5 inclined to correspond with the inclined faces of the side members and fit closely and snugly thereagainst when the diaphragms are set.

As the width of the floor arches vary, we 10 adapt the dome for widths greater than 20 inches by providing inserts 13 that are adapted to fill in between the spaced edges of the top members 3 of the paired dome members, and which are of the same thickness as said top in order to form a smooth 15 upper surface thereacross and obviate unevenness in the tops of the arches and in the thickness of the slabs. These inserts are adapted for support on the upper edges of 20 the diaphragms 10 and are provided with hooks and eyelets adapted for communication with the hooks and eyelets on the top members 3 of the dome body, the hooks and eyelets alternating in their arrangement, in 25 order to properly connect the top members of the paired bodies with each other either directly or through the intervening insert 13, each dome being preferably provided 30 with three sets of the hooks and eyelets in order to form an effective connection between the parts.

It is apparent, however, that if desired, the hooks and eyelets may be omitted and temporary battens 16 nailed to the under 35 faces of the top members 3 and the inserts 13 and removed when the dome is to be taken down.

In order to give a clear understanding of the purposes and use of the dome we have 40 shown the same with supporting soffits and part of a floor slab, 15 designating the supporting studs, 17 the temporary form beams and 18 soffit boards that are carried by the beams 17 and in turn support the dome and 45 form the bottoms of the form for the concrete floor beams.

In using the domes, assuming that the same are constructed and assembled as described, should a slab, having an arch width 50 of 20 inches, be under construction, the body members 1-1' are used alone and are set up by opening the side and top members 2-3 to the obtuse angle and connecting the top members 3 of the opposite like members 55 by the hooks and eyes 8-9 or the temporary battens 16. After the members of the dome are connected as described, the diaphragms or cross members 10 are set by placing the same between the sides 2 within the shoulders 11 of the battens 4 and pressing the same to place, so that the sides 2 are extended and held in position by abutment of the ends of the diaphragms against the inner faces of said side members. The domes are 60 then set on the soffit boards and bridge the 65

spaces therebetween, the lower edges of the side members 2 resting on the tops of the soffit boards adjacent the edges thereof, so that not only is the space between adjacent soffit boards covered by the arch of the 70 domes, but there is space left between the side members 2 of adjacent domes within which the floor beam 20 of the slab 21 is formed when the concrete is poured, the 75 domes being arranged on the soffit boards in longitudinal alinement across the space to be floored so that continuous arches and floor beams may be formed.

With the domes arranged as described, the concrete is poured therebetween to form 80 the floor beams and thereover to a desired depth to form the slab 21, the connection between the dome members being sufficiently close to avoid flow of concrete therebetween, and the diaphragms 10 at the ends of the 85 last domes in a row preventing flow of the concrete into the domes. Should it be desired, however, to form an arch of greater than 20 inches in width an insert 13 is located between the spaced edges of the top 90 members 3 of each dome and the top members 3 connected with each other and with the inserts by means of hooks 8 and eyes 9, or by means of temporary battens 16, longer 95 diaphragms 10 being used with the wider domes in order to set the domes for a greater width.

When the inserts 13 are used, we prefer to break the joints between the inserts and domes by extending the inserts from the ends 100 of the domes, and as the width of the domes are the same throughout the width of the slab, projecting ends of the inserts may extend between the top members of abutting 105 domes, with the result that the domes are keyed together to retain the same in alinement, the ends of the inserts abutting to obviate openings therebetween through which concrete may pass.

When the slab and floor beams have been 110 formed about and over the domes, and the concrete is set sufficiently to permit the domes to be removed, the body portions of each dome are separated along the top by disconnecting the hooks 8 from their eyelets 9, or by removing the temporary battens and removing the diaphragms 10, so 115 that there is no support for the hinged top members nor obstruction that would prevent the inward collapse of the sides.

The top members 3 are then pulled downwardly on their hinges to separate the same from the bottom of the slab and the sides 2 then drawn away from the sides of the floor beam 20, so that the mold members may be 120 removed from the slab and from the soffit without disturbing the soffit. In order to permit the top members 3 to fold downwardly without marring the slab or injuring the domes, we round the inner edges of 125

the top members, as at 22, on a radius from the hinged joint, so that the said edges may turn freely in the corners of the arches.

By locating the hinges on the inner surfaces of the battens 4—5, as distinguished from connecting the same with side members 2 and top 3, we provide for holding the top and side members in parallel relation, and thereby obviate possible damage to the dome bodies or to the hinge, and also adapt the bodies to fold parallel with each other and thereby save space in storing or shipping.

Having thus described our invention what we claim as new therein and desire to secure by Letters-Patent, is:

1. A dome for concrete structures comprising separate, paired body members, each including a side and top having hinge connection, means on said side for supporting a cross member, a cross member supported on said means, and an insert adapted for location between the facing edges of the top members and support on said cross members.

2. In a dome for concrete construction, a body formed in sections, each section comprising side and top members, means connecting the tops of opposite paired members to form an integral structure thereof, and cross members adapted for support on the sides of said sections and spacing the same to retain the dome in functional position.

3. In a dome for concrete construction, a body formed in separate sections each comprising a top and side member, an insert removably located between the top members of the separate sections, and means connecting said sections to retain the parts in functional position.

4. In a dome for concrete construction, a body formed in separate sections each comprising a side and top member, a support on each side member, a batten on each top member arranged to lie along the side on the said support when the parts are collapsed, an inwardly operating hinge con-

necting said batten with a relative side member, means for connecting the separate sections to retain the dome parts in functional position and cross members removably supported on said supports to retain the parts in spaced relation.

5. The combination with a plurality of domes arranged in longitudinal alinement and each comprising paired body portions, means connecting said body portions to retain the dome in functional position and an insert located between the top members of adjacent domes to spread said top members and connect the domes in longitudinal alinement.

6. The combination of a plurality of domes, arranged in longitudinal alinement and each comprising paired body portions, consisting of hingedly connected side and top members, cross members extending transversely between the side members of each dome and retaining the top members in spaced relation, means for connecting the top members of each dome, and an insert located between the facing edges of each top member and projecting from its dome into a like space in an abutting dome, for the purpose set forth.

7. The combination of a plurality of domes, each consisting of paired body members comprising hingedly connected side and top members, an insert located between the spaced edges of the top members of each dome and projecting from the end of one dome into a like space in an abutting dome, means connecting the top members of said domes with the insert to retain the top members and insert in functional relation, and cross members supported on and extending between the side members and supporting the tops and inserts.

In testimony whereof we affix our signatures.
